GENEVA GEARING

William H. Witte, Kansas City, Mo., assignor to
General Vender Manufacturing Company, Kan-
sas City, Mo., a corporation of Missouri

Application April 2, 1941, Serial No. 386,481

3 Claims. (Cl. 74—436)

This invention relates to vending machines and particularly apparatus for controlling the movement of a rotatable support for the articles being vended.

One of the important aims of this invention is the provision of control apparatus for vending machines in the nature of those shown in U. S. Letters Patent No. 2,154,388, and the primary aim of this invention is to provide a latch for the rotatable support whereby said support is secured against unauthorized and undesirable actuation through engagement by means other than parts of the vending apparatus.

Vending equipment with which control apparatus embodying the instant invention is particularly adaptable, is likewise shown in application Serial No. 273,006, wherein I appear as co-inventor with Eben M. Calder.

It has heretofore been determined that the bottle supporting rack in vending apparatus disclosed in the aforesaid patent and application for Letters Patent, may be moved by applying force thereto, through the delivery opening of the vending machine case or container, and since it is desirable to employ the series of slots on the periphery of the bottle support and not add to the parts of the equipment, a specially designed latch has been created and associated with the support and Geneva gear wheel.

In the drawing:

Fig. 1 is a fragmentary sectional view through a portion of a vending apparatus illustrating the manner of applying movement controlling parts made in accordance with the present invention, taken on line I—I of Fig. 2.

Fig. 2 is a fragmentary sectional view taken on line II—II of Fig. 1.

Fig. 3 is a similar sectional view illustrating the Geneva wheel in another position and the latch in the operative condition; and

Fig. 4 is a fragmentary sectional view with the Geneva gear wheel and latch in inverted plan.

Container 6 of conventional character has a cover 8 thereon that carries coin operated mechanism 10 for operating the Geneva gear wheel, generally designated by the numeral 12.

A bottle support 14 rotatably mounted on cover 8 has a series of alternately spaced indentations 16 and slots 18 on its periphery to be engaged respectively by the cam members 20 and pins 22, the medial portions of which enter slots 18 for the purpose of imparting driving force to support 14. When cams 20 engage arcuately shaped indentations 16, the parts will be locked against relative movement if the mechanism in coin ac-

tuated structure 10 is locked. In some instances and under some conditions however, mechanism 10 is not locked and access to support 14 permits objectionable actuation of the parts of the apparatus which supports the bottle or other articles being sold through the medium of the machine.

To positively preclude movement of support 14 during times when cam members 20 are supposed to be locking the support 14 against rotation, latch 24 is added in a manner illustrated in the drawing. This latch is pivotally supported intermediate its ends by a boss 26 mounted on the underside of cover 8 adjacent Geneva gear wheel 12.

One end of latch 24 has a laterally extending ear 28 positionable within slots 18, while the other end is in the nature of a finger 30 disposed in the path of travel of the depending portions 32 of said wheel 12. A spring 34 mounted on boss 26 yieldably urges ear 28 against the arcuately shaped indentations 16 of support 14 until the latter reaches a position where ear 28 is forced into one of slots 18.

As illustrated in Fig. 3, the thickness of ear 28 is slightly less than the width of slots 18 and therefore, when Geneva gear wheel 12 is rotated from the position shown in Fig. 3, one of pins 22 will be given an opportunity of engaging finger 30 to lift ear 28 from within a slot 18 before the said pin enters another of the slots 18 to impart force to support 14.

The employment of a latch such as just described, eliminates the necessity of providing a ratchet of any type for support 14, and the conventional Geneva gear wheel 12 already found to be a desirable element in vending apparatus, is used to operate latch 24. The latch is positive in its functioning as means for precluding the movement of support 14 in either direction about its pivotal support, and functions more positively than is the case where effort is made to include movement arresting parts in the coin controlled mechanism 10.

Having thus described the invention, what is claimed as new and desired to be secured by Letters Patent is:

1. In apparatus of the character described, a container; a support rotatably mounted in said container having a series of alternately spaced indentations and slots on its periphery; a drive member having portions engageable in the slots and indentations of the support respectively; and a latch engageable in one of the slots when one of the portions of the members is in engagement with an indentation of the support, said latch

having a part disposed in the path of travel of certain of the portions of the drive member whereby to withdraw the latch from the slots as driving force is imparted to the support.

2. In apparatus of the character described, a container; a support rotatably mounted in said container having a series of alternately spaced indentations and slots on its periphery; a drive member having portions engageable in the slots and indentations of the support respectively; and a latch engageable in one of the slots when one of the portions of the member is in engagement with an indentation of the support, said latch having a part disposed in the path of travel of certain of the portions of the drive member whereby to withdraw the latch from the slots as driving force is imparted to the support, said latch being mounted on the case and provided

with a spring to yieldably urge the latch toward the indentations and slots in the support.

3. In apparatus of the character described, a container; a support rotatably mounted in said container having a series of alternately spaced indentations and slots on its periphery; a drive member rotatably mounted on the container comprising cam members for engaging the indentations and pins for entering the slots; and a latch mounted on the container comprising a finger on one end in the path of travel of the pins, an ear on the other end movable toward and from the slots, and a spring for urging the ear toward the support, said ear being in one of the slots when one of the cam members is in engagement with an indentation of the support.
